 Servel, Inc., New York, N. Y., a corporation of
 Delaware

Application May 13, 1950, Serial No. 161,826

1 Claim. (Cl. 62—106)

1

The present invention relates to ice making machines and more particularly to a construction of ice forming mold for such machines.

One of the objects of the invention is to provide an improved mold construction which facilitates the freezing of liquid in and the removal of ice cubes from individual cells so as to reduce the time required and the amount of ice melted during an ice forming and releasing operation.

Another object is to vent the mold so as to break the air seal between the cubes and cells in which they are frozen.

Still another object of the invention is to provide an ice forming mold in the form of an inverted tray having a grid therein to provide adjacent cells and vent openings for the cells in the top wall of the mold.

These and other objects will become more apparent from the following description and drawing in which like reference characters denote like parts throughout the several views. It is to be expressly understood, however, that the drawing is for the purpose of illustration only and not a definition of the limits of the invention, reference being had for this purpose to the appended claim. In the drawing:

Fig. 1 is a diagrammatic view of an ice making machine illustrating the novel ice forming mold of the present invention in perspective;

Fig. 2 is a sectional view of the mold showing the platen moved to an inclined position to open the bottom of the mold;

Fig. 3 is a sectional view through a portion of the mold and showing ice formed in the cells of the mold; and

Fig. 4 is a view similar to Fig. 3 showing the ice released from the individual cells of the mold and the vent openings overlying the individual cells to facilitate the removal of the ice by gravity.

In the drawings, the invention is shown applied to an ice making machine comprising a freezing mold 5 in the form of an inverted metal tray having a rectangular top 6 and depending sides 7 with cross partitions 8 therein forming a plurality of adjacent cells 9. The partitions 8 are joined to the top 6 and side walls 7 of the mold 5 and to each other as by brazing, soldering or welding and are of less depth than the depending side walls 7 of the mold.

A platen 10 is pressed against the depending side walls 7 of the mold 5 by suitable operating mechanism to close the open bottom of the mold and provide a space between it and the bottom of the partitions 8. Water or other liquid to be frozen is supplied to the interior of the mold 5 by

15 a funnel tube 11 projecting upwardly from the top wall 6 and underlying a water supply pipe 12 controlled by a solenoid operated valve 13. A standpipe 14 is connected to one side of the mold 5 and a ball float 15 in the standpipe is adapted to operate a switch 16 connected to control the actuation of water valve 13.

The mold 5 is successively cooled and heated by a serpentine coil 17 mounted on its top wall 6. Coil 17 has straight sections overlying the partitions 8 and curved end portions connecting the straight sections. Preferably, the coil 17 is attached in good heat conducting relation to the top wall 6 of the mold 5 as by brazing, soldering or welding it thereto. One end of the coil 17 is connected to the refrigerant receiver 18 of a compression type refrigeration system by a conduit 19 having an expansion valve 20 therein. The opposite end of the coil 17 is connected by a conduit 21 to the suction side of a compressor 22 driven by an electric motor 23. The high pressure side of the compressor 22 is connected to a condenser 24 by a conduit 25 and the outlet from the condenser is connected to the receiver 18. A 25 by-pass conduit 26 also is connected between the high pressure side of compressor 22 and the inlet end of coil 17 and a selector valve 27 is provided at the juncture of the coil and conduits 19 and 26. Selector valve 27 connects conduit 19 to coil 17 and closes by-pass conduit 26 when the solenoid is deenergized and connects by-pass conduit 26 to the coil 17 when the solenoid is energized.

Platen 10 is mounted adjacent one side of mold 5 for downward and rocking movement to an inclined position below the mold. Trunnion pins 28 project from the opposite sides of the platen 10 and into one end of links 29, see Figs. 1 and 2, and the opposite ends of the links are 35 pivotally connected to suitable supports 30. Adjustable stops 31 limit the pivotal movement of the links 29 on supports 30 to regulate the downward movement of the platen 10 relative to the mold 5. The platen operating mechanism including push rod 32, see Fig. 2, moves the platen 10 from the closed position illustrated in Fig. 1 to the open position illustrated in Fig. 2 and vice versa.

Preferably, the machine is automatically operated and as illustrated diagrammatically in Fig. 1, the machine is controlled by a thermostat 33 having a thermal bulb 34 responsive to the temperature of the mold 5, a bellows 35 connected to the bulb and a single pole double throw switch 36 operated by the bellows. Switch 36 is so connected in an electric circuit as to engage contact

37 with low temperature contact 38 at a predetermined low temperature of the mold 5, see Fig. 1, which energizes the solenoid of selector valve 27 and actuates the latter to discontinue cooling and initiate heating of the mold. Although not shown, the engagement of contact 37 with low temperature contact 38 will energize a branch circuit including the platen operating mechanism to move the platen from the position shown in Fig. 1 to that shown in Fig. 2 to open the bottom of the mold 5. Such platen operating mechanism and the arrangement of the platen support, the serpentine coil 17 and thermal element 34 of the thermostat 33 are substantially the same as described and claimed in an application for Letters Patent of Dudley R. Cook, Ser. No. 161,824, filed concurrently herewith and entitled Refrigeration. Although not shown, an agitator is preferably provided in the platen 10 for agitating the liquid in the mold 6 during freezing and the mold and platen 10 are enclosed in suitable insulating material I indicated in phantom in Fig. 1, the insulation being split to permit movement of the platen relative to the mold.

The present invention in its broadest aspects comprises a mold having an open side from which ice is discharged together with vent means to break the air seal between the mold and ice frozen therein. More specifically, the invention comprises a mold of the type described in the form of an inverted metal tray having cross partitions therein to provide adjacent cells and a vent opening for each cell in the top wall of the tray. The mold construction provides metal walls on all sides of the cells except the bottom to transfer heat and thereby freeze ice at a maximum rate and the vent means permits the free flow of liquid into cells 9, the agitation of liquid over all surfaces of the cells and adapts ice cubes to fall freely from the mold by gravity without excessive melting.

In the illustrated embodiment of the invention, the top wall 6 of the mold 5 has a vent opening 40 for each cell 9. Each vent opening 40 is in the form of a hole drilled or punched in the top wall 6 and of such a small size as to prevent the free flow of liquid therethrough but large enough to permit air to enter the cells 9. While the vent openings 40 are shown as located centrally over each cell, it will be understood that the vent openings may have other locations and that a single vent opening may communicate with adjacent cells. One form of the invention having now been described in detail, the mode of operation is explained as follows.

For purposes of description it is assumed that the platen 10 is in the closed position illustrated in Fig. 1, the mold contains water or other liquid to be frozen and the selector valve 27 is deenergized so that the mold is being cooled by the evaporation of refrigerant in the serpentine coil 17. The water or other liquid in mold 5 is preferably agitated and being frozen on the walls of the cells 9 which are in direct heat conducting relation to the relatively cold coil 17. As the ice builds up on the sides of the cells 9 it acts as an insulator requiring an increase in the difference in temperature to cause heat to flow therethrough so that the temperature of the mold gradually decreases. During a freezing operation the liquid may enter the vent openings 40, due to agitation of the liquid, and freeze therein as illustrated in Figs. 3 and 4. When the cells are completely filled with ice as illustrated in Fig. 3 the mold 5 will have been cooled to the low temperature at

which the bellows operates contact 37 of switch 35 into engagement with the low temperature contact 38. Engagement of contacts 37 and 38 energizes the solenoid of selector valve 27 to open by-pass conduit 26 and thereby terminate cooling and initiate heating of the mold 5. Simultaneously, the platen 10 is lowered to the position illustrated in Fig. 2 to open the bottom of mold 5.

10 The flow of gas at high pressure and temperature from the compressor 22 and conduit 26 through the coil 17 will transmit heat to the top wall 6 of the mold and from the top wall to the depending sides 7 and cross partitions 8. The heating of these walls will melt the ice at their contacting surfaces to release the ice from the cells 9. Also, due to the heat transfer surface of top wall 6 of mold 5 around the vent openings 40, any ice at the edge of the vent openings will be melted to provide an air space therebetween to vent the top of the cells 9. The close fit of the ice cubes C in the individual cells 9 and the melted liquid therebetween form an air seal which, without vent openings 40, would prevent the cubes from falling freely from the cells. With such an air seal at the sides of the ice cubes C, an excessive amount of ice must be melted and a considerable period of time elapse before air can enter around the sides of the cubes and relieve the 20 partial vacuum in the space S above the top of the cubes.

25 The vent openings 40 in the top of the mold 5, however, avoid such an air seal by permitting air to directly enter the space S between the top 30 of the cells 9 and the ice cubes C so that when their contacting surfaces are released the cubes will fall freely from the cells in the manner illustrated in Fig. 4. In other words, as soon as the bond between the ice cubes C and cells 9 is 35 released, the weight of the individual cubes will 40 cause them to slide downwardly in the cells with equalized air pressure on both the top and the bottom of the cube, see Fig. 4. While the ice releasing operation has been described with respect to individual ice cubes C, the cubes are 45 actually attached to each other by freezing over the bottom of the partitions 8, as illustrated in Fig. 4, so that ice falls from the mold 5 in a single cake and onto the platen 10 where it is 50 broken up into individual cubes.

55 After the ice has been released from the mold 5, the platen 10 is moved from the position shown in Fig. 2 to that shown in Fig. 1 to close the open 60 bottom. The ball float 15 is then in a lowered 65 position which permits switch 16 to complete a circuit through the solenoid for actuating the water valve 13 to supply water through the funnel tube 11 into the interior of the mold. When the proper amount of water has been supplied to mold 5, the float 15 actuates switch 16 to open 70 position to close water valve 13. The temperature of mold 5 immediately increases after the cake of ice has been released and the increase in temperature acting through bulb 34 expands bellows 35 and actuates the switch 36 to open position. The solenoid of the selector valve 27 then is deenergized and the valve moves to close the by-pass conduit 26 for terminating heating and initiating cooling of the mold 5. Thus, a cycle of 75 operation of the machine has been completed and a new cycle of operation initiated.

It will now be observed that the present invention provides a mold construction which facilitates the freezing of liquid therein and the release of ice therefrom so as to reduce the time

required and the amount of ice melted during an ice releasing operation. It will also be observed that the present invention breaks the air seal between the cubes and cells in which they are frozen. It will still further be observed that the present invention provides a novel mold in the form of an inverted tray having cross partitions therein forming adjacent cells with a vent opening for each cell in the top wall of the mold.

While a single embodiment of the invention is 10 herein illustrated and described, it will be understood that changes may be made in the construction and arrangement of elements without departing from the spirit or scope of the invention. Therefore, without limitation in this respect, the 15 invention is defined by the following claim.

I claim:

In an ice making machine, a mold having a top and depending side walls with an open bottom, cross partitions in the mold forming a plurality of cells, a platen for opening and closing the bottom of the mold, a coil overlying the top of

the mold, a heat exchange system connected to said coil to deliver either a cooling or heating medium to the coil to freeze liquid in the mold and release ice therefrom, and a vent opening in the top wall of the mold overlying each cell.

CLYDE E. PLOEGER.
